UNITED STATES PATENT OFFICE.

EUGENE F. OSBORNE, OF ST. PAUL, ASSIGNOR OF ONE-HALF TO HERBERT M. CARPENTER, OF MINNEAPOLIS, MINNESOTA.

STEAM-HEATING APPARATUS.

SPECIFICATION forming part of Letters Patent No. 241,507, dated May 17, 1881.

Application filed April 16, 1880. (No model.)

To all whom it may concern:

Be it known that I, EUGENE F. OSBORNE, of the city of St. Paul, State of Minnesota, have invented certain new and useful Improvements 5 in Steam-Heating Apparatus; and I do hereby declare that the following is a full, clear, and exact description thereof, reference being had to the accompanying drawings, and to the letters of reference marked thereon, which form 10 part of this specification.

The invention herein described relates to devices for regulating or controlling the transmission of steam-heat from one system of pipes to another, which systems have no interior communications with each other, the same being more particularly intended for use in connection with a general steam-heating system for cities and towns, at the several points at which the local heating apparatuses of individual buildings take their heat from the main distributing system. It is thus shown in connection with such a system of general steam-heating in Letters Patent No. 236,247, granted to me January 15 4, 1881.

25 Said invention consists in the matters hereinafter set forth, and pointed out in the claims.

In the drawings, Figure 1 is an elevation, in partial section, of a heat-transmitting device provided with my invention, and Fig. 2 is a vertical section of one form of regulating device 30 detached.

For the purpose of this description the general steam-supply system may be supposed to consist either in a steam-supply pipe leading 35 into a transmitter at the building to be heated, or in a steam-supply and a "condense-water" return-pipe connected with each other through the medium of such a transmitter, said transmitter being the mechanism by means of which 40 the heat of the supply-steam is communicated to the heat-distributing apparatus located within the building to be heated.

In the drawings, the pipes of both the main-supply and the local distributing systems are 45 shown only at their points of connection with the transmitter. The several parts are herein designated by the same letters as in the above-mentioned Letters Patent.

A⁵ represents a steam-supply branch leading 50 into a building from the street-main.

T is a transmitter, which consists of a closed vertical metal cylinder suitably supported in place. Said cylinder is interiorly divided by the two parallel horizontal diaphragms *tt* into an upper chamber, a lower chamber, and a central or intermediate chamber, T'. The upper and lower chambers so cut off, are connected with each other by numerous tubes *t'*, but they have no connection with the chamber T'. The steam-supply pipe A⁵ enters the upper chamber, and 55 the return (or discharge) pipe B⁸ leads from the lower chamber. The central chamber, T', is connected into the local distribution system or circuit, so as to form a part thereof, by the pipes *a* and *b*—*a* being the outflow-pipe leading from 60 said chamber near the top, and *b* the inflow or return pipe leading into said chamber near the bottom.

In the operation of the transmitter, the heat of vaporization, due to a given pressure of the steam supplied through pipe A⁵, is transmitted 70 to the fluid contained in the local circuit T' *a* *b* through the walls of the tubes *t'*. A circulation is thereby induced through said local circuit, the heated fluid flowing outward through 75 *a*, and returning after being cooled, through the pipe *b*. In parting with its heat of vaporization the steam supplied is, of course, condensed. As a consequence the top of the transmitter is occupied by steam and the lower portion by the water of condensation. It is proposed that the water-line shall usually be above 80 the bottom of the tubes *t'*. The heat imparted in the transmitter from the contents of the main circuit or pipe to the contents of the 85 local circuit or system is not only the heat of vaporization in the steam, but is also the heat, or a portion of the heat, of the condense-water, for, as is well known, the temperature of the condense-water at the instant of condensation is equal to that of the steam from which 90 it is condensed, but the water quickly gives off its heat to a contiguous body of lower temperature, so that it is only at the surface of the water that the high temperature mentioned 95 prevails. For the purposes of this description a plane located a short distance below the water-surface may therefore be imagined to exist, above which plane, heat is transmitted from the main to the local circuit or system, and 100

below which, heat is not transmitted. It is clear that if this plane or the parallel water-surface be raised and lowered in the tubes t' the area of heat-transmitting tube-surface will be varied, and the amount of heat transmitted will be correspondingly varied.

For the purpose of automatically raising and lowering the water-level in the tubes t' , and thereby automatically regulating the amount 10 of heat transmitted from the main to the local circuit or system, and for the further purpose of effecting this regulation with reference to the varying expenditure of heat throughout the local circuit, an ordinary pressure-diaphragm regulator, G , may be employed as follows: The upper face of the diaphragm g^4 , Fig. 2, is subjected to pressure from the chamber T' of the local circuit through the pipe g . In the pipe B^8 is located a valve, G' , whose stem 20 g' connects directly, or through the medium of the weight-arm g^2 , with the diaphragm-pin g^3 , so that pressure from the local circuit on said diaphragm g^4 tends to close the valve G' . The weight G^2 , on the other hand, operates through 25 the arm g^2 to oppose the pressure of the diaphragm and to open the valve G' , said arm g^2 being for this purpose appropriately connected with the valve-stem g' and diaphragm-pin g^3 . The pressure on the local circuit being, of 30 course, proportionate with the heat of said circuit, when the latter is less than the degree at which the regulator is set, the valve G' will be opened, and vice versa. The degree of heat required in the local circuit may be varied at 35 will by shifting the position of the weight G^2 on the arm g^2 .

In starting the apparatus, the lower chamber of the transmitter will be empty, and the lower diaphragm will therefore be a medium of heat- 40 transmission as well as the tubes; but the transmitter should be of such dimensions that in ordinary operation the tubes will be partially filled with condense-water.

Gages may be applied to the transmitter, if desired, to indicate the water-level of both 45 circuits in said transmitter.

An automatic air-valve should be applied to the chamber T' , (preferably discharging into the discharge-pipe B^8 if the latter is in a circuit,) and a return-bend trap, n^{18} , of proper head, 50 is inserted in the pipe B^8 , as shown in Fig. 1.

Obviously, instead of the diaphragm-regulator shown, the unequal expansion of different metals may be utilized to effect the regulation required, and the valve G' may be located in either the discharge B^8 , as shown, or in the steam-supply A^5 .

I claim as my invention—

1. The combination, with a steam-supply pipe, a local distributing-circuit, and apparatus 60 for transmitting heat from the former to the latter, of regulating mechanism adapted to be set at will to secure the transmission of any desired amount of heat from the steam of the supply-pipe to the contents of the local distributing-circuit, and also adapted to automatically maintain a practically constant pressure or heat in the local distribution of the degree required, substantially as described.

2. In combination with a steam-supply pipe, 70 a closed local circuit, and apparatus for transmitting heat from the steam of the supply-pipe to the contents of the local circuit, a device or devices actuated by the heat of the local circuit to control the amount of heat transmitted 75 to the contents of said local circuit from the steam of the main supply, substantially as described.

In testimony that I claim the foregoing as my invention I affix my signature in presence 80 of two witnesses.

E. F. OSBORNE.
